N. AUBIN.

Making Oil and Water Gas.

No. 11,714.

Patented Sept. 26, 1854.

UNITED STATES PATENT OFFICE.

N. AUBIN, OF ALBANY, NEW YORK.

GAS-GENERATOR.

Specification of Letters Patent No. 11,714, dated September 26, 1854.

To all whom it may concern:

Be it known that I, N. AUBIN, of Albany, in the county of Albany and State of New York, have invented certain new and useful

5 Improvements in an Apparatus for Making and Preparing Gas for Illumination and for other Purposes; and I do hereby declare that the same are described and represented in the following specifications and drawings.

10 To enable other skilled in the art to make and use my improvements I will proceed to describe their construction and use, referring to the drawings in which the same letters indicate like parts in each of the figures.

15 Figure 1, is a perspective view of the apparatus with my improvements. Fig. 2, is a section of Fig. 1 cut perpendicularly from the line x, x . Fig. 3, is a section cut perpendicularly from the line y, y . Fig. 4, front

20 elevation of the furnace, with the front wall removed to show the steam generator and heater in its separate flue. Fig. 5 perspective view of the interior of the cooler. Fig. 6 plan of the same. Fig. 7 an enlarged sec-

25 tional elevation of the steam generator and heater cut perpendicularly through the center.

In the accompanying drawings A is a furnace of brick, with a fire space A' provided with a grate A² and ash pit A³. There are one or more thin arches A⁴ over and across the fire space which support a platform of fire brick B for the gas generating retort B' to lie upon, and in a measure pro-

35 tect it from the direct action of the fire, and consequently it lasts much longer. It is made of iron open at each end and provided with doors B² B² which are secured to the retort by the bar wedge and bracket

40 B³ as represented, or screw bolts may be used if preferred. The retort B' may be partially covered on the sides with fire brick, which covering may be extended entirely over the top as represented in the drawing

45 if desired.

There is a flue B⁴ around and over the retort B' opening into the chimney C which is provided with a damper C'. The flue B⁴ has another flue C² leading from it up un-

50 der the vessel C³ so as to heat it and the materials in it, from which the gas is to be made, and passes across under said vessel and enters the chimney C as represented; this flue is also provided with a damper C⁴.

55 There is another flue E leading from the

fire space A' up and around the steam generator and heater E' and into the chimney C; this flue is also provided with a damper E².

The steam generator and heater E' consists of two small cylindrical vessels a a' placed upon the opposite sides of a larger one a² which connects a at the bottom and to a' at the top as represented.

E² is a vessel provided with a cock b to supply the generator E' with water through the siphon pipe b' which conducts the water onto pieces of brick, pumice stone or other refractory or porous substance with which the apartments a and a² should be filled as represented in Fig. 3, so as to gradually and regularly convert the water into steam that is introduced into the generator E' and prevents it from assuming a globular form and falling to the bottom and forming steam

70 suddenly and produce an undue pressure in the apparatus. The steam generated as above described is heated to a higher temperature than the retort B' and passes into it through the pipe E⁴ uniting with and aiding

75 in generating the gas which may be made of rosin, oil, grease, turpentine, tar or other substances rich in carbon and hydrogen; at the same time expelling the gas and undecomposed matter from the retort

The cooler F' is a rectangular box made of metal and provided with partitions as represented in Figs. 5 and 6, so arranged that the gas which enters through the pipe F will pass around between the partitions as represented by the arrows and pass out through the pipe F² into the gas holder. The cooler F' is placed in a bath of water F³ with sufficient inclination to run the tar and other condensed matter through the apertures e e in the partitions to the pipe

F^4 where it is drawn off. The top of the cooler may be secured by bolts as represented at e' or otherwise.

The apparatus having been constructed 5 and completed as above described, and the vessel E^3 supplied with water, the vessel C^3 with rosin, oil, or other material from which the gas is to be made and fire made upon the grate A^2 . When the apparatus is sufficiently heated the attendant turns the cocks b and c' so as to supply the requisite quantity of water and melted matter to the respective retorts where the steam and gas is generated and cooled as heretofore described, without coming in contact with water until after it is cooled.

I contemplate that such a number of peep holes may be made in the brick as are necessary to enable the attendant to regulate the 20 heat of different parts as required: and that the apparatus may be modified to suit the circumstances under which it is to be used without departing from the merits of my improvements.

25 The manufacture of gas for illumination has been attended with many disadvantages which have generally prevented its introduction into private establishments or small communities: and when obtained from coal 30 the generating, cooling and purifying apparatus are costly and occupy a large space; requiring a particular study for their proper management; and their very offensive odor excludes them from dwellings. When made from rosin, grease or other materials introduced in a liquid state into a heated retort 35 it is liable to much loss and difficulty, for if the temperature is allowed to rise above the dull red heat (and it is very difficult 40 to keep it at that temperature) a portion of the gas generated on some part of the heated surface is decomposed depriving the gas of some of its illuminating power and carbon which is deposited on the interior of 45 the retort and pipe leading from it so that they are eventually completely clogged. If

the apparatus is kept at a much lower temperature much of the material used is not converted into gas but is carried off in the form of vapor. By the construction of the 50 above described improvements and apparatus I have remedied the above mentioned defects, and overcome the disadvantages which have attended the process heretofore. For by introducing steam into the gas- 55 generating retort heated to a higher temperature than the retort itself I have succeeded in producing more gas from a given quantity of material, possessing greater illuminating power in less time and at a much 60 lower temperature; which being cooled before it comes in contact with water its illuminating properties become fixed so as to be less affected when brought into contact with water; and besides the retort and apparatus is not clogged or choked by its production. In short the result of these improvements has been the production of a larger quantity of illuminating gas at a much 65 lower temperature and far less expense and 70 in far less time; from a given quantity of materials which needs no purifying, possessing greater illuminating power, producing a more brilliant light; without choking or clogging the retorts or apparatus used to 75 make, cool, and convey it.

What I claim as my invention and desire to secure by Letters Patent in the above described apparatus for making gas is—

The combination of the gas generating retort B' with the diaphragm steam generating retort a a^2 charged with porous earth, pieces of brick, pumice stone or some other porous substance substantially as described for the purposes set forth.

In testimony whereof I have hereunto signed my name.

N. AUBIN.
